RICHARD C. RHEA, OF WHITEVILLE, TENNESSEE, ASSIGNOR TO UNDERWOOD TYPE-WRITER COMPANY, OF NEW YORK, N. Y., A CORPORATION OF DELAWARE.

LINE-SPACER FOR TYPE-WRITING MACHINES.

1,229,521.

Specification of Letters Patent. Patented June 12, 1917.

Application filed January 31, 1916, Serial No. 75,386. Renewed October 18, 1916. Serial No. 126,290.

To all whom it may concern:

Be it known that I, RICHARD C. RHEA, a citizen of the United States, residing at Whiteville, Hardeman county, and State of Tennessee, have invented and discovered certain new and useful Improvements in Line-Spacers for Type-Writing Machines, of which the following is a specification.

The present invention relates to line spacing mechanism for type-writing machines and consists in the combinations and arrangements of elements hereinafter described and particularly set forth in the accompanying claims.

15 A purpose of the invention is to provide an adjustable line spacing device which may be conveniently set for limiting the angular turning movement of the platen in accordance with the spacing desired between 20 the lines of the matter to be typewritten, and wherein such spacing may be selected with any desired degree of accuracy.

The invention further contemplates the use of the device on machines employing detents for holding the platen against turning after the spacing operation or during writing and to this end a device is provided for throwing the platen holding detent temporarily out of operative position when the desired adjustment is not exactly that of a tooth pitch or any multiple thereof.

A feature of the invention consists in the provision of a stop clutch which is operated by the line-spacing lever as the latter completes its throw, to grip the platen (or a part connected thereto) and thereby arrest and prevent overthrow of the platen. The stop clutch may be connected with the line-spacing lever or platen driver to rotate idly 40 about the platen axis as the platen is rotated by the driver, and may be arrested by a stop as the platen completes a line-space rotation, said stop re-acting on the clutch to cause it to grip the platen and prevent overthrow thereof.

The stop clutch may be in the form of an expansion clutch comprising gripping arms to be expanded into gripping engagement with an annular surface which may be the 50 inner periphery of a flange on the usual line-space ratchet wheel. One of said gripping arms may be connected to the slide bar or driver actuated by the line-spacing lever, so that the stop clutch is rotated during the 55 driving stroke. The other gripping arm

may carry a pivoted arm which, as the 60 platen, completes a line-space rotation, strikes a stationary stop to swing said arm and cause it, by means of a cam thereon, to spread the clutch arms to grip said wheel. The driver and platen are thus arrested. 65 The said stop may be adjustable to vary the throw of the driver, so that the line-spacing may be adjusted to any desired width. A scale and pointer may coöperate with the adjustable stop to indicate the width of the 70 line-space for which the stop is adjusted.

The driver may be connected to the platen for rotating it, through an expansion clutch comprising gripping arms arranged to be expanded into gripping engagement with 75 a flange of the line-spacing wheel or other part rotating with the platen. The connection between the driving clutch and said driver may comprise an arm having a pivotal connection with the driver and operable 80 by the latter to expand the clutch parts to grip said wheel as the driver commences its driving stroke, so that the platen is rotated thereby during the driving stroke.

The invention is shown by way of illustration in the accompanying drawings wherein:

Figure 1 is a side elevational view of the device partly in section.

Fig. 2 is a section at the line 2—2 of 90 Fig. 1.

Fig. 3 is a top plan view partly broken away.

Fig. 4 is a perspective of the friction clutches and their connecting arm, one of 95 the clutches being detached from said arm to clearly show the structure.

Fig. 5 a perspective view of the control for the detent of the platen pinion.

Fig. 6 a view showing the ratchet detent 100 in operative position, and

Fig. 7 a sectional view of the slide securing clamp of the spacing device.

Referring to the construction in detail 1 designates the platen frame of an Underwood typewriting machine to which the invention is shown as applied, and 2 the platen journaled thereon after the usual manner and having the hand turning wheel 3. A ratchet wheel 4 is suitably secured to the 110 shaft 5' of the platen and is constructed with a rim 6 forming a pair of flanges 7 and 8 as shown in Fig. 2. The wheel 4 is adapted to be operated by the regular spac.

ing lever through the medium of an expansion clutch that frictionally engages with the inner periphery of the flange 8 of said ratchet wheel and which will be hereinafter referred to as the driving clutch. A second expansion clutch, which may be termed a stop clutch, is also actuated by the spacing lever at the completion of the platen-driving stroke, to grip the flange 7 of the line-space wheel to stop the latter and prevent overthrow thereof.

The driving clutch, which is arranged to frictionally engage with the flange 8 of the ratchet wheel 4, comprises a pair of clutch arms or grips 9 and 10 (see Fig. 4) in the form of disk-like members centrally cut away as at 11, to fit over the platen shaft, said clutch arms being connected at their lower ends by a pivot 50 permitting the upper ends of the clutch arms to be spread, thereby expanding the clutch to grip the inner peripheral surface of the flange 8. On the upper end of the clutch member 9 is an arm 12 connected thereto by a pivot 51, said arm having a cam surface 52, which, when the arm 12 is swung to the left (Fig. 4) about its pivot, bears against an arm 31 fixed to and projecting upwardly beyond the upper end of the clutch member 10. Thus the movement of the arm 12 about its pivot is effective to expand the clutch into frictional holding engagement with the line-space wheel 4. The arm 12 has an opening 53 in which is a pin 13 on an arm 14, thereby pivotally connecting the latter with the clutch member 9. The arm 14 is pivotally mounted on a reciprocating slide bar or driver 15 by a screw 16 (see Figs. 1 and 3). The bar 15 is supported to reciprocate on bearings 17 and 18 on the platen frame, and is actuated by the usual line-spacing lever, which, at each operating stroke, engages the forward end of said bar and drives the latter rearwardly or to the left (Fig. 1), and thereby actuates the clutches, as herein-after explained. The driver 15 is returned by a spring 20 connected at one end to a pin 19 on the driver, the forward end of the spring being anchored to the platen frame.

When the driver 15 commences its driving stroke, it operates through the arm 14 to swing the arm 12 of the driving clutch to lock the latter to the line-space wheel, and thus to the platen. The driver is then operative during the remainder of the driving stroke to rotate the platen. As the driver 15 returns, it first swings the arm 12 to the right, so that the driving clutch is released and then returned with the driver to starting position while the platen remains at rest. The extent of rotation of the platen, at each operation of the driver, depends on the length of the stroke of the driver, and this is regulated by an adjustable stop. The

latter controls the action of the stop clutch, which is automatically brought into operation at the completion of the driving stroke, to grip the line-space wheel, arrest the platen, and prevent overthrow of the platen.

The stop clutch comprises clutch parts or grips 9^a and 10^a connected by a pivot 50^a, said grips located within the outer flange 7 of the ratchet wheel and adapted to be spread into clutching engagement therewith. Fixed to the member 9^a is an arm 12^a having an opening 53^a to receive a pivot pin 13^a on an arm 55 fixed to the arm 14. The clutch arms 9^a and 10^a are spread by means of an arm 31^a connected by a pivot 51^a to the clutch member 10^a and having a cam surface 52^a to bear against the fixed arm 12^a when the arm 31^a is swung about its pivot. During the driving stroke of the driver 15, the stop clutch 9^a, 10^a rotates idly with the platen by means of its connection through the arms 14 and 55 to said driver. As the driver completes its stroke, the arm 31^a engages a stop 30, thereby expanding the stop clutch 9^a, 10^a, to grip the line-space wheel, and at the same time stopping the rotation of the clutch, so that the driver is arrested and the platen stopped. The stop clutch is effectual to prevent overthrow of the platen as said clutch is positively arrested, and the greater the force applied to the driver tending to cause overthrow of the platen, the more powerful is the gripping action of the clutch to prevent overthrow.

The stopping device comprises a plate 23 having the stop lug 30 which arrests the clutch arm 31^a. The plate 23 is slidably mounted on a cover plate 21 secured by screws 22 to the platen frame and forming a part thereof. The plate 23 has a finger-piece 24 for adjusting the same. A screw 25, fixed in the cover plate 21 and having a knurled nut 26, passes through a slot 27 in the plate 23 and through an opening in a clamping plate 28 overlying the plate 23. By setting up the nut, the plate 23 is secured in adjusted position. The clamping plate 28 carries a pointer 29 that indicates the adjustment of the plate 23 by a scale marked on the plate 23.

The ratchet 32 of the wheel 4 is adapted to be engaged by a detent for holding the latter against accidental turning and said detent consists of an arm 33 pivotally mounted on the pin 34 and a roller 35 carried by the arm engages with the teeth 32 in the usual manner. A spring 36 normally acts on the arm 33 to hold the detent in operative position.

It is sometimes necessary to space the lines of typewriting matter in such a way that the distance between them may not agree with the size of the teeth of the platen, as for instance on ruled paper, and it is therefore proposed to move the detent tem-

porarily from operative position. To this end a releasing device 37 is formed with a flange 38 (see Fig. 5) fitted on the rim of the wheel 4 and said flange is constructed with an inturned portion 39 that works between said wheel 4 and the member 40 on the platen shaft 5. A cam track 41 is formed on the member 37 and engages the grooved roller 42 mounted on the detent arm 33 and said cam track operates to move the detent from operative position by angularly shifting said lever by the handle 43. At its respective ends the cam track 41 is hooked forming stops 44 and 45 that engage with the roller 42 and determine the angular movements of the detent control. The member 37 is held in position on the ratchet wheel by means of the spring-pressed detent arm 33.

20 It is obvious that those skilled in the art may vary the details of construction and arrangements of parts without departing from the spirit of the invention and therefore I do not wish to be limited to such features except as may be required by the claims.

Having thus described my invention what I claim as new and desire to protect by U. S. Letters Patent is:

30 1. In a type-writer spacing mechanism the combination of the platen having a wheel, a friction clutch comprising a pair of pivotally connected and separable members adapted to engage said wheel, an arm carried by one of said clutch members, a reciprocable bar pivotally connected to said arm for actuating the clutch to operate the platen, an arm carried by the other clutch member, and an adjustable stop coöperable 40 with the second clutch arm to limit the turning movement of the platen, substantially as described.

2. In a type-writer spacing mechanism the combination of the platen having a flanged wheel, a friction clutch comprising a pair of separable semi-disk members arranged concentric with and adapted to engage the flange of said wheel, arms carried by said disk members respectively, a reciprocable bar pivotally connected to one of said arms for actuating the clutch to operate the platen, and an adjustable stop coöperable with the second clutch arm to limit the turning movement of the platen, substantially as described.

3. In a type-writer spacing mechanism the combination of the platen having a double flanged wheel, a pair of friction clutches arranged concentric with and adapted to engage the flanges of said wheel respectively, a pair of arms carried by said pair of clutches, a reciprocable bar pivotally connected to said arms for actuating the clutches to operate the platen, and an adjustable stop coöperable with one of the

clutches to limit the turning movement of the platen, substantially as described.

4. In a type-writer spacing mechanism the combination of the platen having a double-flanged wheel, a pair of friction clutches comprising each two separable semi-disk members adapted to engage the respective flanges of said wheel, arms carried by said pairs of disk members, a reciprocable bar connected to said arms for actuating the clutches to operate the platen, a second arm carried by one of said clutches, and an adjustable stop coöperable with said second arm to limit the turning movement of the platen, substantially as described.

5. In a type-writer spacing mechanism the combination of the platen and the supporting frame therefor, means for imparting rotation to the platen comprising separable friction disks, an arm carried by one of said disks, a plate slidably mounted on the frame, a device for securing said plate in different adjusted positions, and a stop member carried by the plate adapted to engage said disk arm and lock said disk to the platen to limit the turning movement thereof, substantially as described.

6. In a type-writer spacing mechanism the combination of the platen having a ratchet wheel, means for imparting rotation to the ratchet wheel, a detent comprising a pivotally mounted arm carrying a roller engaging with the teeth of the ratchet wheel, means for predetermineding the turning movement of the ratchet wheel, an angularly shiftable member mounted on the ratchet wheel and held thereon by said detent arm, and a cam track carried by said member engaging with said detent arm and operable to shift the same from operative position, substantially as described.

7. In a type-writer spacing mechanism the combination of the platen having a ratchet wheel, means for imparting rotation to the ratchet wheel, a detent comprising a pivotally mounted arm carrying a roller engaging with the teeth of the ratchet wheel, means for pre-determining the turning movement of the ratchet wheel, an angularly shiftable member mounted on the ratchet wheel and held thereon by said detent arm, a grooved roller mounted on said detent arm, a cam track carried by said shiftable member engaging with said grooved roller and operable to shift the detent arm from operative position, and stops formed on said cam track for limiting the angular movement of said shiftable member, substantially as described.

8. The combination of a platen, and means to line-space the platen, comprising a manually-operated driver, a clutch moved idly by the driver during its driving stroke, and means to arrest the movement of said clutch, to permit the driver to actuate the clutch and cause it to hold the platen.

9. The combination with a rotary platen, of a manually-operated driver, means connecting the driver with the platen for rotating the latter, a stop clutch connected to the driver to be rotated thereby with the platen, a clutch-operating device carried with the clutch and movable relatively thereto to actuate the clutch, and a stop in the path of said device to arrest it and cause said relative movement, thereby causing the clutch to grip the platen or a part rotating therewith, and thus arrest the platen and driver.

10. The combination with a rotary platen, of a manually-operated driver, means connecting the driver with the platen for rotating the latter, a stop clutch connected to the driver to be rotated thereby with the platen, a clutch-operating device carried with the clutch and movable relatively thereto to actuate the clutch, a stop in the path of said device to arrest it and cause said relative movement, thereby causing the clutch to grip the platen or a part rotating therewith, and thus arrest the platen and driver, said stop adjustable to vary the stop position of the clutch, and a scale and pointer relatively adjustable by the adjustment of the stop to indicate the distance through which the platen will be rotated by an operation of the driver.

11. In a typewriting machine, the combination with a rotary platen, of a reciprocating driver, means connecting the driver with the platen for rotating the latter, a stop clutch comprising gripping arms, means providing an annular surface rotatable with the platen and with which said arms may be brought into gripping engagement, one of said arms connected with the driver to cause the clutch to oscillate as the driver reciprocates, a clutch-operating device carried by the other gripping arm and operable by a movement relative thereto, to cause said arms to grip said surface, and a stop in the path of said clutch-operating device to arrest it, and thereby actuate the clutch to hold the platen and arrest the driver.

12. In a typewriting machine, the combination with a rotary platen, of a reciprocating driver, means connecting the driver with the platen for rotating the latter, a stop clutch comprising gripping arms, means providing an annular surface rotatable with the platen and with which said arms may be brought into gripping engagement, one of said arms connected with the driver to cause the clutch to oscillate as the driver reciprocates, a clutch-operating device carried by the other gripping arm and operable by a movement relative thereto, to cause said arms to grip said surface, a stop in the path of said clutch-operating device to arrest it, and thereby actuate the clutch to hold the platen and arrest the driver, an adjusting plate carrying said stop and adjustable to vary the position of said stop, a thumb screw to clamp said

plate in adjusted position, a scale on said plate, and a pointer along which the scale moves as the plate is adjusted, to indicate the length of line-space for which said stop is adjusted.

13. The combination with a rotary platen, of a manually-operated driver for rotating the platen step by step, a clutch comprising gripping arms, a clutch-holding member connected to rotate with the platen, and having an annular flange with which the clutch arms are expansible into gripping engagement, one of said arms connected to the driver to cause the latter to oscillate the clutch about the platen axis as the driver reciprocates, a cam pivoted on the other gripping arm, and a stop in the path of said cam operable as the clutch is rotated by the driver to arrest said cam, thereby causing a relative movement of the cam and its carrying arm whereby the clutch is operated to grip said annular flange, and thereby arrest the driver and platen.

14. The combination with a rotary platen, of line-spacing mechanism comprising a reciprocating driver, an expansion clutch connected with the driver to oscillate about the platen axis as the driver is reciprocated, and means to actuate said clutch as the driver completes a driving stroke, to cause the clutch to hold the platen, and thereby arrest the driver and platen.

15. The combination with a rotary platen, of line-spacing mechanism comprising a reciprocating driver, an expansion clutch connected with the driver to oscillate about the platen axis as the driver is reciprocated, and a stop to arrest the clutch and throw it into gripping engagement with a part rotating with the platen, to arrest the platen and driver.

16. The combination with a rotary platen, of a line-space ratchet wheel comprising an annular flange, a reciprocating driver for effecting line-space rotations of the platen, a stop clutch comprising pivotally connected gripping arms, one of which is connected to the driver to oscillate the clutch as the driver reciprocates, a clutch actuator carried by the clutch, and a stop in the path of said actuator to arrest it at the completion of a driving stroke, and thereby cause it to expand the clutch arms to grip said flange and arrest the platen.

17. The combination with a rotary platen, of a line-space ratchet wheel comprising an annular flange, a reciprocating driver for effecting line-space rotations of the platen, a stop clutch comprising pivotally connected gripping arms, one of which is connected to the driver to oscillate the clutch as the driver reciprocates, a clutch actuator carried by the clutch, a stop in the path of said actuator to arrest it at the completion of a driving stroke, and thereby cause it to expand the

- clutch arms to grip said flange and arrest the platen, a detent cooperating with said line-space wheel to hold it at line-space positions, determined by the ratchet teeth on said 5 wheel, means for holding the detent off the ratchet wheel, and means to adjust said stop for arresting the platen at positions intermediate the line-space positions determined by the ratchet wheel and detent.
- 10 18. The combination with a rotary platen, of a manually-operated driver, a clutch connected thereto to drive the platen during the movement of the driver in one direction, a second clutch connected to be moved idly 15 about the driver as the latter is moved in said direction, and means to arrest said second clutch and actuate it to hold the platen, and thereby arrest the platen and driver.
19. The combination with a rotary platen, 20 of a manually-operated driver, a clutch connected thereto to drive the platen during the movement of the driver in one direction, a second clutch connected to be moved idly about the driver as the latter is moved in 25 said direction, and means to arrest said second clutch and actuate it to hold the platen, and thereby arrest the platen and driver, said clutches both movable idly about the platen axis in the reverse direction and 30 thereby returnable with the driver to starting position while the platen remains at rest.
20. The combination with a rotary platen, of a manually-operated driver, a driving clutch actuated thereby to rotate the platen, 35 and a holding clutch actuated by the driver to arrest the platen.
21. The combination with a rotary platen, 40 of a reciprocating, manually-operated driver, a driving clutch, a connection between said clutch and driver for actuating the clutch as the driver commences its driving stroke, to connect the clutch and platen, and cause the platen to be rotated by the clutch during the driving stroke, a 45 holding clutch connected to the driver to be moved idly therewith during the driving stroke, and a stop operable to arrest the holding clutch and actuate it to grip the platen and arrest the latter.
- 50 22. The combination with a rotary platen, of a manually-operated reciprocating driver,
- a driving clutch and a holding clutch both connected to the driver to oscillate about the platen axis as the driver reciprocates, the connection of the driver with the driving 55 clutch being operable to cause the latter to drive the platen as the driver moves in one direction, and means to actuate the holding clutch as the driver completes its driving stroke, to hold the platen, said holding 60 clutch being normally disconnected from the platen during its oscillation in both directions.
23. The combination with a rotary platen, 65 of a reciprocating driver, means providing an annular clutch-holding surface rotatable with the platen, an expansion clutch comprising gripping arms expandable into gripping engagement with said surface, and a connection between said driver and clutch 70 for operating the latter as the driver commences its driving stroke to connect the clutch with the platen and cause the clutch to rotate the platen during the remainder of the driving stroke, said clutch being automatically released from the platen and returned with the driver.
24. The combination with a rotary platen, 75 of an expansion clutch comprising arc-shaped grips pivotally connected at one end, 80 means providing an annular gripping surface into engagement with which said grips are expandable, a cam carried by one of said grips and operable by a movement relative thereto to spread said grips into gripping engagement with said surface, and a reciprocating driver connected to said cam for actuating the clutch when the driver commences its driving stroke and causing the clutch to rotate the platen during the driving stroke, 85 said cam operated by the driver to release the clutch as the driver commences its return stroke and return the clutch with the driver to starting position.
- In witness whereof, I have hereunto set 90 my hand and seal at Whiteville, Tennessee, this 21st day of January, A. D. nineteen hundred and sixteen.
